Primary Examiner — T Chase Nelson*Assistant Examiner* — Jeff Lenard D Torres(74) Attorney, Agent, or Firm — Greer, Burns & Crain, Ltd(57) CLAIM

The ornamental design for a footwear midsole as shown and described.

DESCRIPTION

FIG. 1 is a front perspective view of a footwear midsole showing my new design;

FIG. 2 is a rear perspective view thereof;

FIG. 3 is a front elevational view thereof;

FIG. 4 is a rear elevational view thereof;

FIG. 5 is side elevational view thereof;

FIG. 6 is an opposite side elevational view thereof;

FIG. 7 is a top plan view thereof; and,

FIG. 8 is a bottom plan view thereof.

The even broken lines in FIGS. 1-8 represent portions of the footwear midsole and environmental structure that form no part of the claimed design. The uneven broken lines which define the bounds of the claimed design form no part thereof.

1 Claim, 8 Drawing Sheets(56)
